UNITED STATES PATENT OFFICE.

ROBERT T. POLLOCK, OF NEW YORK, N. Y., ASSIGNOR TO UNIVERSAL OIL PRODUCTS COMPANY, OF CHICAGO, ILLINOIS, A CORPORATION OF SOUTH DAKOTA.

PROCESS AND APPARATUS FOR CRACKING OIL.

Application filed April 11, 1921, Serial No. 460,525. Renewed March 15, 1928.

This invention relates to improvements in process and apparatus for cracking oil and refers more particularly to a vaporizing chamber used in connection with the cracking or conversion of hydrocarbon oils.

Among the salient objects of the invention are to provide a chamber which has provision for separation of the vaporous portion from the liquid portion and maintaining

10 a concentrated flow of the liquid portion to a drawoff line whereby any deposited material is carried with the flow and not permitted to collect and accumulate in the passage nor to hinder the process in any way 15 by the clogging or choking of the apparatus; to provide a process in which the vaporous portions are released from the liquid portions at different stages in their travel to the drawoff line and allowed to collect in 20 the top of the chamber where they are drawn off by vapor line connected therewith.

In the drawings:

Fig. 1 is a view showing the interior of the vaporizing chamber with parts in section.

25 Fig. 2 is a plan of the apparatus on line 2—2 of Figure 1.

In the drawing is shown only that portion of the cracking system which is essential to the understanding of the invention. The 30 heating zone and the condensing apparatus have been purposely omitted in order to reduce as much as possible the complication that would involve their explanation and in that any type of heating means and condensing means may be employed with this 35 type of vaporizing chamber and also the feature of the invention being entirely in the vaporization of the oils, the explanation will be restricted to that portion of the apparatus.

40 Heated oil, having been raised to a cracking temperature in the heating means or heating coil (not shown) is introduced through the transfer line 1, controlled by a valve 2, which rises vertically through the 45 center of the vaporizing chamber shell 3 through the line 4. In the vicinity of the top of the chamber, the vertical line 4 reverses its direction in the gooseneck 5 and travels downwardly forming a spiral coil 6, 50 passing off as a drawoff line 7 near the bottom of the vaporizing chamber. At intervals along its travel there are tapped into this spiral coil a plurality of vapor risers 8, which connect directly with the coil and 55 extend upward to a height above the top of

the gooseneck 5 so that any liquid level which might have a head in the gooseneck 5 will not flow from the top of the risers. The oil entering the vertical pipe 4 rises and flows downwardly through the spiral coil 60 6. The oil being at a cracking temperature, there will be released from the oil body vapors which will pass out through the vapor risers 8.

Continuously during its travel down 65 through this spiral coil, vapors will be released and will rise and as explained pass out into the open chamber 3 where they will pass off through the vapor line 9 to the condensing apparatus not shown. Any condensate which is refluxed in the vaporizing chamber may be drawn off through the line 10 controlled by a valve 11 and returned to be reheated in the heating tubes. The higher 70

boiling point fractions which fail to vaporize in the vapor chamber, together with the carbon and heavy residual material will pass off through the line 7 controlled by a valve 12 and may be directed to storage or to other distilling apparatus. 80 By permitting the oil to vaporize in this manner, a constant flow of liquid oil will be kept flowing through the spiral tube and any accumulation of carbon which may tend to collect will be washed away with this 85 liquid flow. The fact that there are a series of vapor risers at different points in the spiral coil communicating directly with the upper portion of the vapor chamber allows ample opportunity for the vaporized portion of the oil to pass off to the condensing apparatus. In addition to the obviating of 90 the carbon difficulties, the circulation of the heated liquid oil fractions back through the vaporizing chamber and out through the 95 drawoff line 7 keeps the interior of the vaporizing chamber at all times at high temperature and facilitates the redistillation of any oil fractions which may tend to reflux in the vaporizing chamber, that is there are 100 numerous oil fractions which, if the oil was permitted to rise directly into the top of the vapor chamber and there pass off in the form of vapors would condense and fall back as reflux condensate and due to the fact that 105 there is a large amount of heat given up in the vaporization of the oil, these oil fractions would remain as a liquid condensate. By circulating the hot residuum together with the higher boiling point hydrocarbons which 110

are of such character that they do not vaporize at the temperature to which they have been subjected in the heating zone, the heat content in these oil fractions may be utilized to re-distill these lighter condensates as the heated liquid flows back down through the vaporizing chamber. This, together with the elimination of carbon difficulties, serves to increase materially the yield of high quality distillate in the cracking apparatus. It is, of course, understood that more than one of these vaporizing chambers may be connected to a single heating means and various types of heating means may be used for heating the raw oil prior to its introduction to the vaporizing chamber and different forms of condensing apparatus may be connected therewith for condensing the vaporized oil drawn off from the vaporizing chamber through the vapor line 9. The outflow from the line 7 may be re-distilled as may the condensate from the line 10.

I claim as my invention:

1. The process of vaporizing hydrocarbon oils, which consists in passing oil that has been heated in a furnace to a distilling temperature in a restricted stream through a vaporizing zone located outside of the furnace where no rise in temperature of the oil occurs, in releasing vapors from said stream

into said zone at different intervals during the travel of the oil through said zone in said restricted stream.

2. A process for vaporizing hydrocarbon oil, consisting in introducing the oil to a vaporizing zone while at a conversion temperature in a restricted stream, advancing said stream under pressure, removing the vapors generated at spaced intervals from said restricted stream, utilizing the heat in the unvaporized portion of the oil in said stream to distill the condensate refluxed in the vaporizing zone and in continuously discharging residual oil and suspended carbon remaining in said stream from the vaporizing zone.

3. An apparatus for vaporizing oil comprising a vaporizing chamber through which heated oil is passed, a coil for circulating heated oil extending through said chamber, vapor discharge conduits communicating with the coil at different portions thereof for discharging vapors from the coil into said chamber, a vapor outlet from the chamber, means for discharging unvaporized oil from the lower part of said chamber, and means for discharging reflux condensate from said chamber.

ROBERT T. POLLOCK.
